(57) **CLAIM**

The ornamental design for jewelry, as shown and described.

DESCRIPTION

The patent or application file contains at least one drawing/photograph executed in color. Copies of this patent or patent application publication with color drawing(s)/photograph(s) will be provided by the Office upon request and payment of the necessary fee.

FIG. 1 is a front view of jewelry showing my new design;

FIG. 2 is a rear view thereof;

FIG. 3 is a side view thereof;

FIG. 4 is an opposite side view thereof;

FIG. 5 is a top perspective view thereof;

FIG. 6 is a bottom perspective view thereof;

FIG. 7 is a partial enlarged front view of the area shown in the dot-dash broken line rectangle in FIG. 1 labeled as FIG. 7;

FIG. 8 is a partial enlarged front view of the area shown in the dot-dash broken line rectangle in FIG. 1 labeled as FIG. 8;

FIG. 9 is a partial enlarged front view of the area shown in the dot-dash broken line rectangle in FIG. 2 labeled as FIG. 9;

FIG. 10 is a partial enlarged rear view of the area shown in the dot-dash broken line rectangle in FIG. 5 labeled as FIG. 10; and,

FIG. 11 is a partial enlarged rear view of the area shown in the dot-dash broken line rectangle in FIG. 6 labeled as FIG. 11.

The dot-dash broken lines depict enlargement areas and form no part of the claimed design.

1 Claim, 7 Drawing Sheets
